UNITED STATES PATENT OFFICE

130,492

DESIGN FOR A PORTABLE TRAFFIC COUNTER HOUSING

Hervey L. MacCowan, Wilmette, Ill., assignor to
Streeter-Amet Company, Chicago, Ill., a cor-
poration of Illinois

Application May 9, 1941, Serial No. 100,864

Term of patent 14 years

To all whom it may concern:

Be it known that I, Hervey L. MacCowan, a citizen of the United States, residing at Wilmette, in the county of Cook and State of Illinois, have invented a new, original, and ornamental Design for a Portable Traffic Counter Housing, of which the following is a specification, reference being had to the accompanying drawing, forming part thereof.

The single figure in the drawing is a top perspective view of a portable traffic counter housing showing my new design. The concealed sides

of the housing (opposite those visible in the drawing) are plain, and the contour of the concealed sides of the top corresponds with that of the sides which are visible.

The characterizing feature of the design resides in the traffic counter housing disclosed having a carrying handle of the configuration, and nested in the top thereof, as shown.

I claim:

The ornamental design for a portable traffic counter housing, as shown and described.

HERVEY L. MACCOWAN.
